UNITED STATES PATENT OFFICE.

BERT R. WILLIAMSON, OF FAIRFIELD, MAINE, ASSIGNOR TO KEYES FIBRE COMPANY,
OF WATERVILLE, MAINE, A CORPORATION OF MAINE.

SUCKER-HEAD FOR PULP-MOLDING MACHINES.

1,364,229.

Specification of Letters Patent.

Patented Jan. 4, 1921.

Application filed October 17, 1919. Serial No. 331,348.

To all whom it may concern:

Be it known that I, BERT R. WILLIAMSON, a citizen of the United States, residing at Fairfield, county of Somerset, State of Maine, have invented an Improvement in Sucker-Heads for Pulp-Molding Machines, of which the following description, in connection with the accompanying drawing, is a specification, like characters on the drawing representing like parts.

This invention relates to a pick off or sucker head for a pulp molding apparatus. A device of this general type is disclosed in the patent to Keyes No. 740,023, granted September 29, 1903. Such a sucker head is employed to pick off the moist and more or less limp article such as a pie plate or butter dish from the mold in which it has been formed in order to transfer it to another position such as onto a drying apparatus.

Such a sucker head is of a general cup shape and has its mouth covered with finely reticulated material such as a wire screen. This screen prevents the article from being sucked up into the sucker head and enables the suction to be applied throughout the surface with which the sucker head contacts and also, when compressed air is blown through the sucker head to remove the article, enables it to be readily removed.

The object of the present invention is to provide a means for securing the reticulated material to the sucker head in such a manner that a smooth and even face shall be presented for contact with the article and so that the reticulated material may be readily removed when worn or injured and readily replaced.

These and other objects and features of the invention will appear more fully from the accompanying description and drawings and will be particularly pointed out in the claims.

The drawings illustrate a sucker head of a type adapted to be used on an apparatus for molding pie plates.

In the drawings—

Figure 1 is a side view partially in vertical section of a sucker head.

Fig. 2 is a plan view on a smaller scale of the face of the sucker head.

The general construction and operation of an apparatus for molding pulp articles is fully set forth in the patent to Keyes above

referred to, and patents which have been granted subsequently, so that no detailed description is necessary.

The sucker heads, as in the said Keyes patent, are usually mounted at the ends of hollow radial arms which revolve about a central axis. Suitable connections are made by which a source of vacuum and a source of compressed air are put into communication at the required times with the sucker head.

At the completion of the molding operation of the pulp article such as a pie plate, it is presented on one of the mold members by which it is made, and it is the object of the sucker head to remove this moist and more or less limp article from the mold member. To effect this the sucker head descends and rests upon the surface of the pulp article. Suction is then applied to the sucker head and usually compressed air blown up through the mold member. The pulp article thus clings to the sucker head and the sucker head is then revolved or moved to carry the article to a desired position, such for example as over a conveyer running to a drying apparatus. The suction or vacuum in the sucker head is then broken and preferably compressed air forced through the sucker head thus causing the article to be discharged from the sucker head.

It is very important that the face of the sucker head shall fit snugly against the article so as to insure the maintenance of the vacuum by which the article is held to the sucker head; that the face of the sucker head shall be covered with the reticulated material so that the article shall not be drawn up into the hollow sucker head; and that the sucker head shall not injure or mar the surface of the pulp article while contacting with and holding it.

It is also important that the construction shall be such as to permit the removal and replacement of the reticulated material in order to take care of wear and damage thereto. The present invention presents a simple and effective means for securing these results.

The sucker head, in the form illustrated, is shown as made of metal and having a flat cup-shaped base 1. The hollow neck 2 extends into a sleeve 3 connected to a hollow head 4 in turn connected to a hollow arm 5. The arm 5 supports and carries the

sucker head and affords the passage way to the sources of vacuum and compressed air.

The rim 6 of the cup-shaped base has its face 7 beveled outwardly and rearwardly 5 and has its exterior periphery 8 screw threaded.

An annular clamping member 9 is internally threaded to fit on to the threaded periphery 8 of the rim of the cup-shaped 10 base. This annular clamping member 9 has an inwardly projecting flange 10 beveled on its rear face to correspond with the beveled face 7 of the rim.

The reticulated material 11 is in the form 15 of a disk of fine wire screen. This disk is laid over the mouth of the base with its peripheral edge overlying the beveled rim face 7. The clamping member is then placed in position and screwed down until its 20 beveled surface coöperating with the beveled rim face firmly clamps the reticulated disk in place.

The annular clamping member is so proportioned that its outer face 12 is either behind 25 or in the plane of the outer face of the reticulated disk 11 when the clamping member is in place. This insures a smooth and flat surface contacting with the pulp article and prevents any undesirable marking or 30 injury of the article when handled by the sucker head.

The annular clamping member 9 is provided with spanner holes 13 by which it may be gripped and turned and the base 1 is also

provided with spanner holes 14 by which 35 it may be held.

Whenever the reticulated disk becomes worn or injured all that it is necessary to do is to unscrew the annular clamping member, take out the worn or injured disk, replace it with a fresh one, and screw the annular clamping member back in place. 40

Having thus described my invention what I claim as new and desire to secure by Letters Patent is—

1. A sucker head for pulp molding apparatus comprising a cup-shaped base having the face of its rim beveled outwardly and rearwardly, a reticulated disk covering the mouth of the base with its peripheral edge overlying the beveled rim face, and an annular clamping member fitting over and removably secured to the rim of the base and presenting an inwardly projecting beveled flange to fit against the peripheral edge of 55 the disk and clamp it to the beveled rim face with the face of the annular member in or behind the plane of the outer face of the disk.

2. A sucker head for pulp molding apparatus comprising the construction defined in claim 1 in which the cup-shaped base is externally threaded and the annular clamping member is internally threaded to effect their removable securing together. 60

In testimony whereof, I have signed my name to this specification.

BERT R. WILLIAMSON.
